UNITED STATES PATENT OFFICE.

ADOLPH C. BROSE, OF NEW YORK, N. Y.

APPARATUS AND METHOD FOR IMPRINTING HARD-RUBBER ARTICLES.

1,410,732.

Specification of Letters Patent. Patented Mar. 28, 1922.

Application filed February 16, 1921. Serial No. 445,279.

To all whom it may concern:

Be it known that I, ADOLPH C. BROSE, a citizen of the United States, and a resident of the city of New York, borough of the 5 Bronx, county and State of New York, have invented certain new and useful Improvements in Apparatus and Methods for Imprinting Hard-Rubber Articles, of which the following is a description.

10 The present invention relates to the method of marking or impressing articles formed of hard rubber or the like and having attractively finished surfaces.

15 The general object of the invention is to provide a method of marking identifying characters, such as trade marks, names and the like on the surfaces of such articles as fountain pens, combs, etc., formed of hard rubber and after the articles have been finished and the surfaces thereof rendered attractive in the usual manner as by polishing or by coating the same with suitable material.

20 To this end the invention resides in softening the area or section of the surface to be marked by exposing the same to the action of heat and then impressing or indenting this softened area with a cold metallic marking die which operates to transfer the 25 design thereof to the softened area and at the same time absorbs from the outlining edges of the indentations forming the characters, the heat already applied thereto, so that the outlines of the characters are 30 formed clear and well defined and the characters themselves rendered readily distinguishable, and, if so desired, conditioned for a coating of contrasting coloring material such as gold leaf which may be applied 35 simultaneously with the forming of the characters.

40 Other objects will appear and be better understood from an embodiment of the invention of which the following is a specification:

45 A work-holder and marking die together with a holder for carrying out the present method of marking hard-rubber articles and the like are illustrated in the drawings forming part of the specification and in which—

50 Figure 1 is a perspective showing the relative positions of the parts of the work-holder and marking die in operative relation together with the heating plate which is shown by dotted lines;

55 Figure 2 is a transverse section through

the work-holder also showing the marking die in end elevation and arranged so as to engage the work.

The bed plate 5 or other part of a suitable 60 press is adapted to provide the lower section of a work-holder. For this purpose the said bed plate may be provided with a suitable groove or recess or otherwise formed so as to engage the work. For purposes of illustration a concave groove or recess 6 is shown as being formed in the bed plate 5 and disposed to co-operate with a similar shaped groove 8 in the upper section 7 of the work-holder, which section 7, 65 is adapted to be superimposed on the lower section 5 so that the grooves 6 and 8 co-operate to receive the work 9, which is herein shown as a finished hard rubber barrel or reservoir of a fountain pen. An opening 10 70 in the upper section 8 of the work-holder is in alignment with a marking die 11 which, for purposes of illustration, I have shown as consisting of a number of bars of ordinary printing type which are secured 75 in any preferred manner to the movable element 12 of a press which may be constructed and arranged so as to reciprocate vertically or move in any other desired manner, the arrangement being such that upon movement of the element 12 in one direction the type of the marking die 11 moves into contact with an area of the surface of the work 9 by passing through the openings 10 in the section 8 of the work-holder. 80

85 The surface of the work 9 is finished or rendered glossy either by polishing or by a coating of shellac or the like. In indenting or impressing articles of hard rubber such as the specimen illustrated it is necessary to soften the article by the application 90 thereto of heat. But if the barrel 9 were heated throughout and to an extent to render the same sufficiently soft so as to be readily impressed by the marking die, the 95 heat would necessarily soften the surface coating and render the same fluid so that the utility of the coating would be destroyed. It is, therefore, important in the use of the present invention to confine the 100 heat to the area or section of the surface to be impressed and with the present method this confinement or control of the heat is made possible through the use of a heater constructed so as to co-operate with the 105 work-holder. For purposes of illustration I have shown the heater as consisting of 110

a plate 13 formed of clay carbon having a handle 14 constructed so as to support the plate 13 in a fire which may be a bunsen flame. When the temperature of the plate 5 is raised to the required degree the plate is superimposed on the upper section 7 of the work-holder and over the opening 10 thereof. This step exposes the area of the surface of the barrel directly underneath 10 the opening 10 to the action of the heat from plate 13, which operates to soften the said area so that when the plate 13 is withdrawn and the movable element 12 lowered the marking die 11 operates to impress the softened area of the barrel upon moving into 15 contact therewith. It will be noted that the marking die is a cold die as distinguished from a die heated by suitable appliances. This provision of a cold die is 20 of importance in that when the same moves into contact with the softened area of the work the heat is readily absorbed or taken up by the die. Thus the material of the surface of the work entering the interstices 25 of the die is quickly cooled during the compression of the surrounding material in contact with the relief portions of the die. This results in imparting a sharp outline to the characters impressed in the work by 30 the die.

The method of this invention readily lends itself to impressing colored characters in the work. When gilt characters for instance, are to be formed, the area to be 35 impressed is coated with the usual sizing liquid consisting of gelatin or the like after which a coating of gold leaf enamel ink or its equivalent is applied over the sizing coat. The work is then arranged between 40 the sections 5 and 7 of the work-holder and the heater having been heated to the required extent is then placed over the opening 10 of the upper section 8 of the work-holder and when the area exposed through 45 the opening 10 is rendered sufficiently soft by the action of heat, the heater is removed after which the die 11 is lowered into contact with said exposed area. Only a relatively small amount of pressure on the part 50 of the marking die 11 is required to effect the indentation of the softened area of the barrel and the duration of this pressure need be for only a few seconds after which the movable element is removed from the 55 work-holder whereupon the work may be taken from the work-holder and from the press.

The present invention has considerable utility in connection with instances where 60 manufacturers of combs, fountain pens, etc., formed of hard rubber, celluloid or the like, deliver these articles in finished condition, that is to say, with glossy surfaces, to distributors who desired that the articles 65 be marketed with a trade mark name or

the like. In such cases the present invention enables the distributor to apply the required marking without injury to the finished surface so that the expense which would otherwise be incurred by refinishing 70 the surfaces of the articles after marking the same in accordance with old methods, is eliminated.

Although I have shown and described an ideal form of the invention it is to be understood that I am not to be limited to the details of procedure set forth it being obvious that the equivalent of this and changes within the scope claimed, may be made use of without departing from the spirit or 80 sacrificing any of the advantages of the invention.

I claim:

1. The method of marking the finished surfaces of hard rubber articles and the 85 like, which consists in softening the area of the surface to be marked by exposing the same to the action of heat and impressing the said area with a cold metallic marking die. 90

2. The method of marking the finished surfaces of hard rubber articles and the like, which consists in confining the application of heat to the area of the surfaces to be marked until the said area has been rendered soft, and then impressing the said softened area with a cold metallic marking die. 95

3. The method of marking the finished surfaces of hard rubber articles and the 100 like, which consists in embracing the surface of the article to be marked by a perforated work-holder, directing heat to the area of said surface immediately surrounded by the perforation of the work-holder until the said 105 area has been rendered soft and impressing the said softened area by passing a cold metallic marking die through the perforation of the work-holder and into contact with the said softened area. 110

4. The method of marking the finished surfaces of hard rubber articles and the like, which consists in coating the area of surface to be marked first with an adhesive and then with coloring matter, arranging the article in a perforated embracing work-holder so that the coated area aligns with the perforation of the work-holder, directing heat to the coated area through the perforation of the work-holder until the said area 115 has been rendered soft and then passing a marking die through the perforation of the work-holder and into contact with the coated area. 120

5. In apparatus for marking the surfaces 125 of hard rubber articles and the like, a work-holder made up of separable sections having co-operating engaging structures for receiving the work to be marked and surrounding the same, one of said sections having an 130

- opening through which a section of the surface of the work engaged thereby is exposed, means for heating the said exposed section of the work through the said opening, and
- 5 a marking die movable through the said opening and into contact with the said exposed section of work.
6. In apparatus for marking the surfaces of hard rubber articles and the like, a work-
10 holder made up of separable superimposed sections adapted for receiving between them the work to be marked and further adapted
- for engaging the work during the marking thereof, one of said sections having an opening disposed so as to expose there-through the work engaged by the said section, means for directing heat through the opening of the said section and into contact with the work and a marking die for engaging the work and movable through said opening. 20
- In testimony that I claim the foregoing as my invention, I have signed my name.

ADOLPH C. BROSE.
